COMBINED DOOR AND MIRROR SUPPORT

Filed Feb. 12, 1927

UNITED STATES PATENT OFFICE.

DAVID ALONZO MARTENS, OF NEW YORK, N. Y., ASSIGNOR TO SARAH LYNAGH
MARTENS, OF NEW YORK, N. Y.

COMBINED DOOR AND MIRROR SUPPORT.

Application filed February 12, 1927. Serial No. 167,827.

This invention relates to a combined door and mirror construction, and has particular reference to a door for bathroom medicine cabinets.

At the present time the mirror is usually rigidly supported by or upon the outer surface of the door of the medicine cabinet, which cabinets are usually positioned in the wall directly above the lavatory. This arrangement is disadvantageous in that the user in many instances, is unable to closely observe the reflection. It is also obvious that the mirror is limited for swinging movement with and in the same direction as the door, whereas in many instances to obtain the proper light it is essential to swing the mirror in a different direction as well as to tilt the same.

It is therefore the principal object of the present invention to provide in combination with a medicine cabinet door or other swinging closure, a mirror support which permits of substantial universal movement and adjustment of the mirror to obtain the best light and to dispose the same in a sufficiently projected relation to the wall surface as to bring it in close proximity to the user.

Other objects and advantages reside in the simplicity of construction, the economy with which the same may be produced, and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of a medicine cabinet having a door constructed in such a manner as to provide an adjustable mirror support and illustrating the mirror supporting means adjusted to partially project the mirror from the face of the door;

Fig. 2 is a fragmentary sectional plan view taken approximately on the line 2—2 of Fig.

3, with the door partially opened in full lines and with the same fully closed in broken lines;

Fig. 3 is a vertical sectional view taken approximately on the line 3—3 of Fig. 1, with the mirror supporting means fully closed.

Referring to the drawings by characters of reference, 10 designates a medicine cabinet having hinged thereto at 11, a door 12. A panel including sections 13 and 14 hingedly connected to each other by hinges 15, is attached to the outer face of the door by hinges 16, which hinges preferably connect the section 13 to the door adjacent the free side edge so that the panel is adapted to swing upon its hinges in an opposite direction from the direction in which the door swings. The meeting edges of the panel sections 13 and 14 are cut away respectively at 17 and 18 intermediate the height of said edges. A frame 19 having upper and lower rearwardly projecting bearing ears 20, is fulcrumed upon the hinge pins of the panel section connecting hinges 15 so that when the panel sections are disposed at an angle to each other, the frame 19 which is of a height slightly less than the cut-out portions 17 and 18, may be swung laterally and independently of the panel sections. A mirror 21 is arranged in a frame 22, which frame is journaled or fulcrumed for vertical tilting, by means of trunnions 23 bearing in the vertical side rails of the frame 19. Under this arrangement it is obvious that the mirror 21 and its frame 22 may be projected outwardly from the door 12 by swinging the panel on its hinges 16 and disposing the sections 13 and 14 at an angle. The cut-away portions 17 and 18 afford a space which allows the frame 19 to swing laterally or horizontally and which further affords a space to permit the vertical tilting of the mirror 21 and its frame 22. If further projection is necessary it is obvious that the door 12 may be swung outwardly to obtain such necessary projection.

Ordinarily the mirror 21 and its frame 22 are swung into the same vertical plane with the frame 19 and the panel sections are swung into alignment with each other on the hinges 15, and thence into flat contact against

the face of the door 12. A suitable latch element 24 is carried by the face of the door to engage over and hold the panel in this position.

5. It is also obvious within the scope of the invention that the panel may serve as a door in lieu of being mounted upon the door, in which instance the panel may either be swung to an open position without disposing 10 the sections 13 and 14 at an angle, or when desired an angular arrangement of the sections may be had.

It is further to be understood that while the device is not particularly intended and 15 described for use in connection with medicine cabinets, the same may be equally as well adapted to a closed door for a full length mirror or to other swinging closures.

What is claimed is:

20 1. An adjustable support for mirrors including a panel having hingedly connected sections, each formed with a medial cut-out portion at the inner hingedly connected edges, and a mirror supporting frame fulcrumed upon the panel sections at the axes of the hinged connection therebetween and adapted when the panel sections are disposed at an angle to each other, to swing laterally with respect thereto, the cut-out portions 25 affording a clearance space for the swinging movement of the mirror supporting frame.

2. An adjustable support for mirrors including a panel having hingedly connected sections, each formed with a medial cut-out portion at the inner hingedly connected edges, a mirror supporting frame fulcrumed upon the panel sections at the axes of the hinged connection therebetween and adapted when the panel sections are disposed at an angle to each other, to swing laterally with respect thereto, the cut-out portions affording a clearance space for the swinging movement of the mirror supporting frame, and means 30 for locking the panel sections in alinement.

3. An adjustable support for mirrors including a panel having hingedly connected sections each formed with a medial cut-out portion at the inner hingedly connected edges, a mirror supporting frame fulcrumed upon the panel sections at the axes of the hinged connection therebetween and adapted when the panel sections are disposed at an angle to each other, to swing laterally with respect thereto, the cut-out portions affording a clearance space for the swinging movement of the mirror supporting frame, and means for locking the panel sections in alinement, said means serving to rigidly maintain the mirror supporting frame against swinging movement when the panel sections are locked thereby in alined relation.

4. A cabinet having an opening therein, a closure for said opening and a mirror support carried by the closure including hingedly connected panel sections, one of said

sections being hinged at one side edge thereof to the closure, and a frame fulcrumed to the panel sections upon the axis of the hinged connection therebetween.

5. A cabinet having an opening therein, a closure for said opening and a mirror support carried by the closure including hingedly connected panel sections, one of said sections being hinged at one side edge thereof to the closure, a frame fulcrumed to the panel sections upon the axes of the hinged connection therebetween, and a mirror mounted for tilting movement within said frame.

6. A cabinet having an opening therein, a closure for said opening and a mirror support carried by the closure including hingedly connected panel sections, one of said sections being hinged at one side edge thereof to the closure, a frame fulcrumed to the panel sections upon the axes of the hinged connection therebetween, a mirror mounted for tilting movement within said frame, and a common means for holding the panel sections in alinement and for retaining the frame and mirror in parallel relation to the alined panel sections.

7. An adjustable support for a mirror, including a panel comprising a pair of sections, a hinged connection therebetween at the upper and lower ends of the inner edges, and a mirror fulcrumed on the axes of the hinged connections between the panel sections whereby to permit of lateral swinging movement of the mirror with respect to the panel sections when said panel sections are disposed at an angle to each other and whereby the mirror is rigidly held against lateral swinging movement with respect to the panel sections when the panel sections are disposed in alinement.

8. An adjustable support for a mirror, including a panel comprising a pair of sections, a hinged connection therebetween adjacent the upper and lower ends of the inner edges, means for locking the panel sections in alinement, and a mirror fulcrumed upon the axes of the hinged connections between the panel sections, whereby to permit of lateral swinging movement of the mirror with respect to the panel sections when said panel sections are released and disposed at an angle to each other and whereby the mirror is rigidly held against relative lateral movement with respect to the panel sections when the panel sections are locked in alined relation.

9. An adjustable support for a mirror, including a panel comprising a pair of sections, hinged connections therebetween adjacent the upper and lower ends of the inner edges thereof, said sections having mating cutaway portions at the inner edges between the hinged connections, means for locking the panel sections in alined relation, a frame fulcrumed

upon the axes of the hinged connections between the panel sections, and a mirror fulcrumed within the frame for tilting movement whereby to permit of lateral swinging movement of the frame with respect to the panel sections and tilting movement of the mirror with respect to the frame when said

panel sections are released and disposed at an angle to each other and whereby the mirror and frame are rigidly held against relative movement with respect to the panel sections when the panel sections are disposed in alinement. ¹⁰
